US00D695111S

(12) **United States Design Patent**
Hansen et al.

(10) **Patent No.:** **US D695,111 S**
(45) **Date of Patent:** **** Dec. 10, 2013**

(54) **BEVERAGE CARTRIDGE**

(71) Applicants: **Nick Andrew Hansen**, Banbury (GB);
Mark Richard Thomas Norton, White Plains, NY (US)

(72) Inventors: **Nick Andrew Hansen**, Banbury (GB);
Mark Richard Thomas Norton, White Plains, NY (US)

(73) Assignee: **Kraft Foods R&D, Inc.**, Northfield, IL (US)

(**) Term: **14 Years**

(21) Appl. No.: **29/433,078**

(22) Filed: **Sep. 25, 2012**

Related U.S. Application Data

(63) Continuation-in-part of application No. PCT/GB2012/050623, filed on Mar. 22, 2012.

OTHER PUBLICATIONS

U.S. Appl. No. 13/612,528, filed Sep. 12, 2012, entitled Cartridges, Systems and Methods for Preparation of Beverages, 38 pages.

(Continued)

Primary Examiner — Thomas Johannes
(74) Attorney, Agent, or Firm — Fitch, Even, Tabin & Flannery LLP

CLAIM

The ornamental design for a beverage cartridge, as shown and described.

DESCRIPTION

FIG. 1 is an upper front perspective view of a beverage cartridge showing our new design;

FIG. 2 is a front elevation view thereof;

FIG. 3 is a lower left side perspective view thereof;

FIG. 4 is a bottom plan view thereof;

FIG. 5 is a left side elevation view thereof;

FIG. 6 is a top plan view thereof;

FIG. 7 is a right side elevation view thereof; and,

FIG. 8 is a back elevation view thereof.

Broken line disclosures in the figures show unclaimed subject matter only and form no part of the claimed design.

1 Claim, 4 Drawing Sheets
